(57) **CLAIM**

We claim the ornamental design for an electronic device zippered sleeve, as shown and described.

DESCRIPTION

FIG. 1 is a front perspective view of an electronic device zippered sleeve;

FIG. 2 is a top plan view of the electronic device zippered sleeve;

FIG. 3 is a bottom plan view thereof;

FIG. 4 is a front elevational view thereof;

FIG. 5 is a back elevational view thereof;

FIG. 6 is a right elevational view thereof;

FIG. 7 is a left elevational view thereof;

FIG. 8 is a front perspective view of the electronic device zippered sleeve in an open configuration;

FIG. 9 is a bottom plan view of the electronic device zippered sleeve in FIG. 8;

FIG. 10 is a top plan view thereof;

FIG. 11 is a right elevational view thereof;

FIG. 12 is a left elevational view thereof;

FIG. 13 is a front elevational view thereof; and,

FIG. 14 is a back elevational view thereof.

The broken lines representing stitching are part of the claimed design.
